(No Model.)

A. E. MÜLLER.

CHRONOMETER ESCAPEMENT.

No. 351,122.

Patented Oct. 19, 1886.

UNITED STATES PATENT OFFICE.

AUGUST E. MÜLLER, OF PASSAU, GERMANY.

CHRONOMETER-ESCAPEMENT.

SPECIFICATION forming part of Letters Patent No. 351,122, dated October 19, 1886.

Application filed April 29, 1886. Serial No. 200,554. (No model.) Patented in England June 6, 1884, No. 8,651; in Germany December 9, 1884, No. 29,728, and in Austria-Hungary January 22, 1886, No. 36,358 and No. 68,665.

To all whom it may concern:

Be it known that I, AUGUST E. MÜLLER, a resident of Passau, Germany, have invented a new and Improved Chronometer-Escapement, 5 (for which I have obtained Letters Patent in each of the following countries: England, No. 8,651, dated June 6, 1884; Germany, No. 29,728, dated December 9, 1884; Austria-Hungary, No. 36,358 and No. 68,665, dated January 22, 10 1886,) of which the following is a specification.

My invention relates to the construction of a chronometer-escapement; and it consists of the various elements of improvement hereinafter more fully set forth.

15 In the accompanying drawings, Figures I and II show plans of the several parts in two positions. Fig. III is an end view of Fig. I, and Fig. IV a diagrammic view showing the action of the teeth of the scape-wheel upon adjacent parts.

The scape-wheel A is provided with teeth a , a' , a'' , a''' , &c., the shape of which will be hereinafter more fully described.

B is an arbor, which is provided with a lifting-tooth, z , and with two fingers, x , x' , between which a recess, d , is made.

C is a ratch-wheel, provided with projections c , c' , forming a fork. The wheel C has also a tooth, k , and a recess, h .

30 H is the balance-wheel attached to an arbor, H', which carries a plate or disk, t , provided with a circular recess, s , to allow the ends of the fork c , c' to pass freely. Below this plate t pallets l and g are attached to arbor H'. The 35 impact from the tooth of the wheel A is received by the pallet l , while a pin, g' , carried by the pallet g , during the reciprocating or swinging motion of the balance H, enters the fork c , c' and oscillates wheel C.

40 The construction of the teeth of the scape-wheel A is more fully shown in Fig. IV. The tops of the teeth are in a line, n , n , passing through the center of the wheel, while the lower surfaces of the teeth are in the direction of a line, m , m , drawn from the extreme point of the teeth to the periphery of a circle, q , q , about one-half the diameter of the outside of the teeth. (See Fig. IV.)

45 When one of the teeth of the wheel A gives the impulse to the pallet l , a tooth, a''' , rests

upon the periphery of the arbor B. (See Fig. IV'.) In this position a tooth constructed in the usual manner would scrape similar to a knife upon the circumference of this arbor, (see dotted lines, Fig. IV',) while a tooth constructed as above described is only tangential to the circumference of the arbor. When the recess d of the arbor B, during its motion in the direction of arrow w , Fig. IV', is on top, tooth a''' of the wheel A falls into the recess. 50 The height of the fall of this tooth a''' extends from the dotted line i to the dotted line i'' , while by teeth constructed in the present shape this height of fall would be from dotted line i to dotted line i'' , (see Fig. IV''), which is more than 55 double. Further, a tooth constructed as above described acts always against the exterior edge of the recess d , while the present construction of the teeth would act against the surface of the recess some distance inside of the periphery of 60 the arbor. (See Fig. IV'') Besides this, the action or impulse of my improved tooth is continuous against the pallet l (see Fig. IV'') during its whole operation, which cannot be obtained by any other construction of teeth. 65

The operation is as follows: Fig. I shows the position of all parts after the impulse has been given. The balance H is swung in the direction of the arrow p , p . In this position the tooth a''' of the wheel A is in a tangential position to the circumference of the arbor B, the lifting-tooth z lies in the recess h of the wheel C, and the finger x is nearly in a tangential position to the periphery of said wheel C. The fork c , c' must remain in the position shown on 70 account of these positions of the tooth z and finger x , and likewise on account of the plate t acting against one of the projections c of the fork. When the balance H moves in the opposite direction, as indicated by the arrow y , y , 75 the pin g' enters the fork c , c' and turns the ratch-wheel C toward the left, pushing thereby the tooth z out of its recess h , thereby turning the arbor B so as to bring its recess d in position to allow the tooth a''' to fall into the same, while 80 the finger x' bears now against the periphery of the wheel C until, by the continued rotation of said wheel C, its tooth k comes in contact with said finger x' , when the ratch-wheel C will be held stationary. When the oscillating mo- 85

tion of the balance H brings the pallet *g* and pin *g'*, and consequently the ratch-wheel C, in the position shown in Fig. II, the tooth *z* is made to fall into the recess *h* on account of the pressure exerted by the tooth *a''* against the edge of the recess *d* in the arbor B. At the same time a tooth of the scape-wheel A falls upon the pallet *l*, and imparts the necessary impulse to the same and to the balance H, the pin *g'* having before this moved out of the fork *c c*, and the several parts will be again brought into the positions shown in Fig. I.

I claim as my invention—

A chronometer-escapement consisting of the

combination of scape-wheel A, with teeth *a a'*, &c., the arbor B, provided with tooth *z*, fingers *x x'*, and recess *d*, the ratch-wheel C, provided with forks *c c*, recess *h*, and tooth *k*, and the balance H, carrying on its arbor H' the plate *t*, pallet *l*, and pallet *g*, provided with pin *g'*, the whole being arranged to operate substantially in the manner and for the purpose described.

AUG. E. MÜLLER.
